A. PEREY,

Making Shot and Shell.

No 39,354

Patented July 28, 1863.

UNITED STATES PATENT OFFICE.

ABIEL PEVEY, OF LOWELL, MASSACHUSETTS.

IMPROVEMENT IN MANUFACTURING BOMB-SHELLS.

Specification forming part of Letters Patent No. 39,354, dated July 23, 1863.

To all whom it may concern:

Be it known that I, ABIEL PEVEY, of Lowell, county of Middlesex, and State of Massachusetts, have invented new and useful Improvements in the Mode and Manner of Manufacturing Bomb-Shells; and I do hereby declare that the following is a full and exact description thereof, reference being had to the accompanying drawings, and to the letters of reference marked thereon, making a part of this specification.

The nature of my invention consists in the arrangement and construction of the reamer, ball-pattern, core-arbor, and core-box, having journals and corresponding shoulders, in combination with a flask constructed with journal-boxes, as hereinafter set forth.

To enable others skilled in the art to make and use my invention, I will proceed to describe its construction and operation.

Figure 1 represents a top view of my revolving flask; Fig. 2, a side view showing the journal-boxes C and gate a; Fig. 3, a sectional view showing the journal-boxes C, the gate a, and core-arbor H; Fig. 4, another sectional view of the flask, showing the journal-boxes C and gate a. Fig. 5 represents a reamer; Fig. 6, the ball-pattern; Fig. 7, the core-box.

A represents the revolving flask with its gate a, that conducts the iron into the center and hollow of the flask, having journal-boxes C at each side of the hollow on a line with the center. The flask rests and revolves upon an upright frame, L. The sand or loam is put in in the ordinary way, and the reamer B is then used to give nearly the size of the intended mold. The reamer-shaft has two wings, B B, made of plates of sheet-iron or other material, semicircular in shape, set on each side of the shaft, and both are adjustable by slats and set-screws b b, as seen at Fig. 5, that one wing may project farther out than the other, so that one wing scrapes and the other cleans or nearly finishes the mold. It rests in the journal-boxes C C of the mold, and is retained in its position by the two shoulders K K. After the reamer is withdrawn, the ball-pattern D, with

a shaft in the center corresponding with the reamer, as shown at Fig. 6, having also shoulders K and journals C similar to the shoulders K and journals C of the reamer, and corresponding with the journal-boxes C of the flask. The ball-pattern D is pressed (or hammered with a mallet) down to its seat, and then revolved in order to smooth and finish the mold by means of the crank d at the end. The core-box E is of the usual round shape, having a neck reamed out the size of the journals C of the ball-pattern and reamer, the distance from the end of the neck to the center of the core-box corresponding with the distance from the inside of the shoulder K of the shaft of the ball-pattern D to the center of the ball-pattern. The core-arbor H, as seen at Fig. 3, has a shoulder, K, corresponding with the shoulder of the shaft of ball-pattern D—that is to say, the distance from the shoulder K to the center being precisely the same—the journal C being likewise of the same diameter, fitting the journal-box C of the flask. After the ball-pattern D is removed and the core arbor H is inserted in the flask A, (before running in the metal,) I insert a common plug or stopper, J, in the lower journal-box C of the flask A, as shown at Fig. 3, so as to prevent the metal from running out of the flask; or, instead of a plug, J, I stop up the journal-box C with sand of the same kind as the rest of the mold, and dry it with the mold before pouring.

What I claim as my invention, and desire to secure by Letters Patent, is—

1. The journal-boxes C of the flask A, as herein described.
2. The reamer, as herein described.
3. The ball-pattern D, as herein described.
4. The core-box, as herein described, all corresponding, so as to fit the journal-boxes C of the flask, for the purpose set forth.

ABIEL PEVEY.
